UNITED STATES PATENT OFFICE.

WILLIAM DUNDAS SCOTT-MONCRIEFF, OF BRIGHTON, ENGLAND.

APPARATUS FOR CHARGING AND DISCHARGING RETORTS.

Application filed March 31, 1922. Serial No. 548,386.

To all whom it may concern:

Be it known that I, WILLIAM DUNDAS SCOTT-MONCRIEFF, a subject of the King of Great Britain, residing at Brighton, in the 5 county of Sussex, England, have invented new and useful Improvements in or Relating to Apparatus for Charging and Discharging Retorts, of which the following is a specification.

10 This invention relates to apparatus for charging and discharging retorts, of the kind wherein the material to be heated in the retorts is arranged on a series of trays which are detachably mounted one above 15 the other on a support whereby the series of trays can be introduced into and removed from the retort by means of an overhead traveller, trolley or the like.

According to my invention, in order to 20 facilitate the introduction into and removal of the trays from the support or cradle, the securing means are arranged to engage with the lowermost tray in such support or cradle, so that the trays of the series can be 25 successively introduced into and removed from the support or cradle from the lower end of the latter. By this means, the trays may be very conveniently piled and unpiled in steps by successively raising and lowering the support or cradle. For this purpose the support or cradle consists of a 30 frame which is adapted to guide the trays either peripherally or internally and is adapted to retain the lowermost tray therein by means of interengaging projections on 35 the tray and frame which can be brought into and out of engagement with each other, e. g. by relative rotation of the tray and frame.

40 In the accompanying drawings, I have shown how my said invention may be conveniently and advantageously carried into practice, viz.—

Figure 1 is a sectional elevation of a retort.

45 Figure 2 is a sectional plan on line 2—2, of Figure 1.

Figure 3 is an enlarged view of portions of the two lower trays showing the suspension rods and rings.

50 Figure 4 is a sectional plan on line 4—4, Figure 3.

Figure 5 is a sectional elevation on line 5—5, Figure 4.

Figure 6 is a sectional elevation of the retort house. 55

Figure 7 is a sectional plan of the retort house.

Figure 8 is a sectional elevation on line 8—8, Figure 7. 60

Figure 9 is a sectional elevation on line 9—9, Figure 7.

Figure 10 is a sectional elevation on line 10—10, Figure 7. 65

Figure 11 is a sectional elevation of a modified form of cradle.

Figure 12 is a horizontal section on the line 12—12, Figure 11.

Figure 13 is a partial transverse section of a tilting table showing means for detachably securing the trays thereon. 70

Figure 14 is a diagrammatic section of the lifting cylinder and control valve.

In giving effect to this invention, I use shallow trays or troughs 1 (see Figures 1 75 to 5) provided with circular bosses or distance pieces 2, cast on them or otherwise suitably attached thereto, and fitting into each other, e. g. they are formed with male and female centres at their upper and lower 80 ends respectively, as shown in Figure 3. These distance pieces 2 are of such height as to cause spaces to be left between the trays for the free passage of the gas or vapour coming from the materials subjected 85 to the process carried on in the retorts.

The lifting of the superimposed trays is effected by means of sling-rods 3, preferably three in number, conveniently made of round or strap metal and riveted or otherwise 90 suitably attached at their upper extremities to the lid 5 of the retort, so as to form a kind of cradle. These rods are held together by metal rings 4, the lower ring being formed with recesses 41, as shown in Figures 4 and 5, so as to enable it to be brought into and out of engagement with projecting lugs 6 on the trays 1, by turning it clockwise or anti-clockwise as required.

The lid 5 is preferably arranged to make a 95 gas-tight joint with the body 7 of the retort, by means of the circular tongue and groove 8, the groove being filled with asbestos, or other suitable packing.

For the purpose of quenching or cooling 100 the carbonized contents of the trays 1, which is a necessary detail in discharging retorts, I provide (see Figures 6 and 7) a

cooling chamber 9 with a circular groove on its upper rim corresponding to the tongue shown on the lid of the retort, and I place the superimposed trays, carried by the slings 5 3 and the lid 5, into the cooling chamber 9, by means of an overhead travelling crane 10, see Figures 6 and 9.

When the material that has been heated in the retort is removed from the cooling 10 chamber 9, I convey it by the overhead traveller to the unpiling platform 11, see Figures 6, 7 and 8. When the traveller has deposited the superimposed trays with the sling rods 3 and the lid 5, on the platform 15 11, it is run back, and connection is made between the cradle 3, 4, 5 and the piston rod of an hydraulic cylinder 13, see Figure 8. The hydraulic cylinder 13 is carried on a support 14, which may 20 be rotated in bearings 15, when it is desired to move the hydraulic cylinder clear of the path of the traveller 10. To unpile the trays, the cradle 3, 4, 5 is suitably lifted by the hydraulic cylinder so as to engage with 25 the projections 6 on the lowest of the trays but one, and all the trays superimposed on the lowest one, are then lifted sufficiently to allow of the lowest tray being drawn away on the rollers 12, and placed upon the tilting 30 platform 16, see Figures 6, 7 and 9.

The movement of the piston in the hydraulic cylinder 13 is conveniently controlled by means of a two-way valve, such, for example, as that shown diagrammatically in 35 Figure 14, where 40 is the high pressure water supply, 41 the exhaust, 42 the casing, 43 the rotary valve, 44 the operating hand wheel, and 45 the pipe connection between the valve and the cylinder 13. The tray is 40 suitably held on to the tilting table 16, which is then turned upside down, and the contents in this way are discharged into a truck underneath, or other suitable receptacle. When the empty tray has been restored to 45 the horizontal position it is released, and moved along the rollers 12, to the loading platform 17, see Figures 6, 7 and 10.

The tray is filled with coal, which has been reduced to sufficiently small dimensions, from a hopper 18, by means of the valve 19, so that the correct quantity of coal is deposited on to each tray. The filled tray is moved along the rollers 12 to the piling platform 20 (see Figures 6 and 7) where 55 the process of superimposing the trays is carried out by means of another hydraulic cylinder 21, which is fixed to a rotating framework similar to that shown in Figure 8 for the unpiling platform. To superimpose the trays, those resting upon the platform 20 are raised by means of a cradle 3, 4, 5 to a height sufficient to allow the next loaded tray to be moved directly underneath the others, and so on until the full number 60 65 has been reached. The cradle 3, 4, 5 bearing

the trays filled with material is then conveyed away by the overhead traveller and the trays lowered into an empty retort. The empty cradle formed by the retort lid 5 and sling rods 3 suspended from the hydraulic 70 cylinder 13, above the platform 11, is then transferred by the overhead traveller to the platform 20, from which it is picked up by the hydraulic cylinder 21. The empty cradle and hydraulic cylinder 21 are then swung 75 aside in order to allow the next set of trays containing carbonized fuel to be conveyed to the unpiling platform 11. The operations of unloading the cradle on the platform 11 and filling that on the platform 20 are then 80 85 repeated as above described.

Any suitable means may be employed for detachably securing the trays on the tilting table 16. For example, the table may be provided on one side with a bracket 30, Figure 13, having a projection 31 for extending over the upper edge of the peripheral wall of the tray 1; and on the opposite side of the table there is pivoted at 32 an arm 33 having a projection 31' for extending over the upper edge of the peripheral wall of the tray. The tray is adapted to be held firmly between the bracket 30 and arm 33 by means of a screw-spindle 34 turning in a nut 35 in a bracket 36 on the table and 90 guided in a bearing 37 in a bracket 38. The inward travel of the arm 33 is limited by means of a stop 39. By turning the screw spindle in one direction or the other the tray 1 can be very conveniently held or released. 100

In the modified form of cradle shown in Figures 11 and 12, the retort cover 5' is secured to a downwardly extending axial tube 22, which is provided at its upper end with an eye 23 whereby it may be secured to the hook of suitable lifting and transporting gear, and has fixed to its lower end a cylindrical member 24, which has bevelled ends and has horizontal projecting surfaces 25, 26 for engaging with members 26, 26 extending inwards from the interior periphery of annular trays 27, 27, in order to support the lowermost tray of the series on the carrier. 110

The members 26, 26 also serve as distance-pieces, for which purpose they are provided at the top with horizontal surfaces 28, 28 on which the trays above rest. They are moreover provided with projections 29, 29 at the top, which extend into and engage with the internal periphery 30 of the tray above, so 120 as to centre the same.

The trays 27, 27 are engaged and disengaged from the cradle by turning the latter relatively to the trays as in the arrangement shown in Figures 1 to 5. 125

By means of this cradle the operations of discharging the retort and recharging the same, by separating the before-mentioned trays, emptying and filling them, and then again superimposing them and placing them 130

in the retort can be carried out as with the cradle first described, as and when required.

The same processes with certain modifications can be carried out for the evaporation 5 of viscous or other liquids, such as tar.

What I claim is:—

1. An apparatus for charging and discharging retorts, said apparatus comprising trays, a carrier for supporting the trays in 10 a superposed condition, horizontally extending surfaces of limited width on the carrier and the trays respectively, said surfaces being adapted to be brought into and out of engagement with each other by turning the 15 carrier and trays relatively to each other.

2. An apparatus for charging and discharging retorts, said apparatus comprising trays, a carrier for supporting the trays in a superposed condition, distance pieces for 20 holding adjacent superposed trays apart, horizontally extending surfaces of limited width on the carrier and on the trays respectively, said surfaces being adapted to be brought into and out of engagement with 25 each other by turning the carrier and trays relatively to each other.

3. An apparatus for charging and discharging retorts, said apparatus comprising trays, a transportable support provided with 30 means for guiding vertically the trays brought into engagement therewith from its lower end, projections on said trays and on said support respectively, said projections being adapted to be brought into and out of 35 engagement with each other by turning the trays and support relatively to each other.

4. An apparatus for charging and discharging retorts, said apparatus comprising a transportable support provided with a top 40 member, downwardly extending sling rods attached to said top member, horizontal surfaces attached to said sling rods at the lower

parts thereof, trays adapted to slide vertically between said sling rods, and projections on said trays adapted to be brought 45 into and out of engagement with said horizontal surfaces.

5. An apparatus for charging and discharging retorts, said apparatus comprising trays, a transportable carrier adapted at its 50 lower end to receive said trays in superposed condition and to deliver them, means for holding and releasing a tray at the lower end of the carrier, a platform for receiving a series of superposed trays connected to a 55 carrier, a tilting section in said platform, releasable means for securing to the tilting section of the platform, a tray released from a carrier, means for transporting a 60 carrier and attached trays relatively to said platform, and means for raising and lowering said carrier and attached trays, for the purposes specified.

6. An apparatus for charging and discharging retorts, said apparatus comprising 65 trays, a transportable carrier adapted at its lower end to receive said trays in superposed condition and to deliver them, means for holding and releasing a tray at the lower end of the carrier, a platform for receiving 70 a series of superposed trays connected to a carrier, a tilting section in said platform, releasable means for securing to the tilting section of the platform, a tray released from a carrier, means for transporting a carrier 75 and attached trays relatively to said platform, and a swing frame bearing a hydraulic cylinder for raising and lowering said carrier and attached trays.
